UNITED STATES PATENT OFFICE.

HARRY J. LEBHERZ, OF FREDERICK, MARYLAND, ASSIGNOR TO THE EVEREDY COMPANY, OF FREDERICK, MARYLAND, A CORPORATION OF MARYLAND.

BOTTLE-CAPPING TOOL.

Application filed December 13, 1924. Serial No. 755,672.

My invention relates broadly to tools and more particularly to the construction of a tool for capping and sealing bottles for the protection of fluid contents thereof.

5 One of the objects of my invention is to provide a simplified construction of capper throat for a bottle capping tool which may be produced inexpensively on a quantity production basis by unskilled labor.

10 Another object of my invention is to provide a construction of bottle capper wherein means are provided for effectively retaining a rubber cushion within the capping throat arranged at all times to readily reject the 15 crown caps from the capping throat after the capping operation.

My invention will be more clearly understood from the following specification with reference to the accompanying drawings, in 20 which:

Figure 1 shows a side elevation of my completed bottle capping tool equipped with the bottle capping throat constructed in accordance with my invention; Fig. 2 is an enlarged 25 cross-sectional view of the bottle capping throat showing the arrangement of spurs on the interior walls of the bottle capping throat, serving to maintain a crown cap extruding gasket in position; Fig. 3 is a plan view looking into the interior of the bottle capping throat and showing the arrangement of the spurs within the throat; Fig. 4 is an enlarged 30 fragmentary view showing the position of the cutting tool in the process of cutting one of the spurs in the interior of the bottle capping throat; Fig. 5 is an enlarged cross sectional view illustrating a fragmentary portion of the wall of the bottle capping throat and the completed spur which has been cut 35 thereon; Fig. 6 is a cross sectional view showing the construction of the cutting tool used in the manufacture of the bottle capping throat in accordance with my invention; and Fig. 7 is a vertical cross sectional view taken 40 through the tool which I have invented for cutting the spurs on the interior walls of the bottle capping throat.

Heretofore in the art bottle capping tools have included as one disadvantage in their 45 construction the defect of the ready loss of the interior washer within the bottle capping throat. When this washer drops out of the bottle capping throat the bottle capper becomes relatively ineffective in the sealing of bottles in that the crown caps tend to hang

in the throat of the bottle capper and destroy the effectiveness of the tool for the succeeding capping operations. By my invention I provide a bottle capping tool in which a plurality of spurs are formed on the interior walls of the bottle capping throat in such manner that the spurs serve to hold a resilient gasket in position at all times. The resilient gasket has the property of extruding the 50 crown cap from the throat at the end of the capping operation enabling the capping throat to be readily raised by angular movement of the bottle capper lever in a position ready for a succeeding operation. In the manufacture of the capper throat according 55 to my invention I provide a movable vertical plunger which is normally resiliently held in its uppermost position to receive and support a bottle capper throat with its resilient gasket therein directly over a hexagonally 60 shaped cutting die. A pressing die is provided which lowers upon the plunger in such manner that the capping throat is rigidly secured between the plunger and the pressing 65 die. In this position the bottle capper throat 70 is ready for a spur cutting operation and any tendency of distorting the bottle capper throat or mashing the same out of shape is eliminated. The pressing die then advances 75 against the resistance of the plunger carrying 80 with it the bottle capper throat and pressing the same over the hexagonally shaped cutting die which operates to cut the spurs on the 85 interior walls of the bottle capper throat. The internal resilient gasket is thereby substantially 90 secured within the bottle capper throat against its displacement or loss. At the end of the spur cutting operation the movement 95 of the pressing die is reversed and on the upper stroke the resilient mounting of the plunger is brought into use for forcing the capper throat from the hexagonally shaped die in a manner in which the capper throat may be readily removed from the tool, the 100 tool being then ready for a succeeding operation.

Referring to the drawings in detail, reference character 1 designates the base of the bottle capping tool having a vertical standard 2 thereon provided with an adjusting 105 rack 3 at its upper extremity. A vertical slideable carriage 4 is provided having a lever 5 pivotally mounted at 6 thereon. The lever is provided at one end with a toothed extension which engages the rack 3 enabling the 110

slidable carriage 4 to be adjusted to any desired position along the standard 2, over the base 1. The slideable carriage 4 carries the bottle capper throat 8 shown more clearly in Fig. 2. The bottle capper throat 8 comprises a cylindrical upper portion 9 of relatively small diameter and a cylindrical lower portion 10 of relatively large diameter connected by a substantially horizontal wall 11. The small cylindrical portion 9 is apertured as represented at 12 enabling a securing bolt 14 to be passed therethrough to support the bottle capper throat upon the vertical slideable carriage 4. Within the cylindrical portion 10 of the capping throat I insert a resilient gasket 15, rounded on its upper edge at 16 and substantially right angled at its lower edge 17. The gasket 15 is centrally apertured at 18 to facilitate the insertion of the gasket 20 within the capping throat as will more fully appear hereinafter.

A series of capping throats such as the capping throat 8 are fed successively upon a plunger 19 illustrated in Fig. 7 disposed concentrically within a die 20 secured as represented at 21 to a base member 22. The plunger 19 is reduced in cross section at its extremity 23 forming an annular shoulder 24 at a distance from the end of the plunger substantially less than the height of the small cylindrical portion 9 of the capping throat 8. The diameter of the extremity 23 of the plunger 19 is slightly less than the diameter of the small cylindrical portion 9 of the capping throat enabling the capping throat to seat snugly upon the extremity 23 of the plunger with the wall 11 resting on the annular shoulder 24 of the plunger 19. The lower edge of the skirt of the cylindrical portion 10 of the capping throat is flared outwardly as represented at 25. A pressing die 26 having a cylindrical bore 27 therein is interiorly shaped as represented at 28 to correspond with the horizontal wall 11 and the cylindrical portion 10 and the outwardly flared skirt 25 of the capping throat 8. The plunger 19 is provided with an annular boss 29 arranged to snugly seat within a vertical guide 30 in the base 22. The lower portion 31 of the plunger 19 is centered through guide plate 32 supported as represented at 33 upon the lower portion of the base 22. The plunger 19 is normally held in its uppermost position by resilient means 34 which in the construction shown is in the form of a rubber cushion. The plunger 19 protrudes through the hexagonally shaped die 20 supporting the capping throat substantially as shown in Fig. 7. The top of the hexagonally shaped die 20 is ground in a concave manner represented at 35 so as to present six sharp cutting points 36, 37, 38, 39, 40 and 41 which become effective to cut and roll up the spurs 42, 43, 44, 45, 46 and 47 on the interior wall of the cylindrical portion 10 of the capping throat 8.

The spurs are each formed as represented in Fig. 4 by the action of the die 20 and the downward movement of the capping throat 8 thereagainst. The cutting point 36 of the die 20 is shown biting into the material of the capping throat 8 and rolling up the material cut therefrom to form a spur 42. The six spurs thus formed cooperate to retain the gasket 15 within the capping throat 8. The spurs are each displaced upwardly from the walls of the cylindrical portion comprising the capping throat leaving a recess in the wall extending into the wall less than one-half the thickness thereof. The outside surface of the wall of the throat is not pierced by the cutting of the spurs and only the inner surface is subjected to the cutting process in the formation of the spurs.

In the quantity production operation of the cutting tool the capping throat 8 is pressed on the extremity 23 of the plunger 19 and the pressing die 26 lowers upon the capping throat. The rubber gasket 15 within the capping throat has its apertured portion 18 seating snugly upon the upper cylindrical portion of the plunger 19 immediately below the shoulder 24. The capping throat is advanced upon the hexagonal guide 20 and seats perfectly thereon for the spur cutting operation in a manner in which the throat is prevented from being mashed out of shape or distorted as the pressing die 26 continues to advance, pressing the capping throat downwardly upon the cutting points of the hexagonal guide 20, the spurs are cut and rolled up against the rubber gasket 15. On the upward stroke of the press the rubber gasket 15, by reason of its resilient properties, forces the throat up off of the die 20 and the operation is complete. The throat can then be readily removed from the plunger 19 and the operations repeated for successive capping throats which are successively fed upon the plunger.

It will be understood that any number of spurs may be cut in the capping throat for insuring the retention of the rubber gasket therein. The spurs serve to secure the resilient gasket in such a position that it is effective to push the crown caps out of the capping throat after the crowning operation upon a bottle.

While I have described my invention in certain particular embodiments, I desire that it be understood that modifications may be made and that I intend no limitations upon the invention other than those imposed by the scope of the appended claims.

What I claim and desire to secure by Letters Patent of the United States is as follows:

1. A bottle capping throat comprising a pair of cylindrical portions, one of said portions having a relatively small diameter and the other of said portions having a relatively

large diameter, a resilient gasket positioned in said portion of relatively large diameter and a plurality of horizontally projecting spurs interiorly formed on the inside wall of 5 said last mentioned cylindrical portion for securing said resilient gasket in position, each of said spurs being displaced upwardly from the wall of said cylindrical portion leaving a recess in said wall extending into 10 said wall less than one-half the thickness thereof.

2. A bottle capping throat comprising a pair of cylindrical portions of differing diameters, one portion constituting a support 15 and the other portion constituting a cap receiving throat, a resilient gasket in said cap receiving throat and tapered members terminating in points and formed integral with the interior wall of said cap receiving throat 20 and projecting horizontally inwardly for securing said resilient gasket in position within in said cap receiving throat.

3. A bottle capping throat comprising in combination a cup shaped member, a resilient 25 gasket seated in the closed end of said cup shaped member and a plurality of teeth each of V-shaped contour and extending radially inwardly from the interior walls of said cup shaped member in a plane at right angles to 30 the wall of said cup shaped member for securing said resilient gasket in position.

4. A bottle capping throat comprising in combination a cup shaped member a resilient

gasket and a plurality of teeth each tapering to a spur point and formed integral with the 35 interior wall of said cup shaped member diametrically opposite each other and extending radially inwardly in a plane at right angles to the wall of said capper throat for supporting said resilient gasket in position. 40

5. A bottle capping throat comprising in combination a cup shaped member a rubber gasket and a plurality of V-shaped spurs formed from the material of the interior wall of said capper throat and extending 45 substantially at right angles to the wall of said capper throat for supporting said rubber gasket in position the exterior wall of said capper throat having its continuity unbroken immediately adjacent each of said 50 spurs.

6. A capper throat for bottle capping tools comprising a cylindrical member having a cap receiving portion, a gasket fitted within said cylindrical member and a plurality of 55 tapered spur members displaced from the material of said inside wall of said cylindrical member immediately adjacent the cap receiving portion of said throat and projecting inwardly normal to the inside wall of 60 said cylindrical member in a plane which contains the lower surface of said gasket for supporting said gasket within said capper throat and impeding the removal thereof.

HARRY J. LEBHERZ.
